O. F. FUETTERER

FLUE CONNECTION

Filed July 21, 1925

UNITED STATES PATENT OFFICE.

OTTO F. FUETTERER, OF HUNTINGTON BEACH, CALIFORNIA, ASSIGNOR, BY MESNE ASSIGNMENTS, TO MARGARET E. FARLOW, OF VAN NUYS, CALIFORNIA, AND JENNINGS B. COLEMAN, OF SAN FRANCISCO, CALIFORNIA.

FLUE CONNECTION.

Application filed July 21, 1925. Serial No. 45,127.

This invention relates to a flue end connection which is especially adapted for use in boilers of the fire-tube type, such as are employed in locomotives, marine boilers and 5 the like, for attaching the flue ends to the tube sheet of the fire box end of the boiler.

An object of this invention is to provide a connection between the flue end and the tube sheet, which is of such character as to 10 insure the formation of a tight joint which is capable of withstanding the strain due to expansion and contraction to such an extent as to reduce to a minimum the possibility of 15 loosening of the joint, thereby obviating leakage of the joint to a large degree.

With the foregoing objects in view, together with such other objects and advantages as may subsequently appear, the invention 20 consists generally in forming a flue sheet with a flue end receiving opening, the inner margin of which opening is countersunk to provide a recess to form the inner rim of the opening, and in providing a flue end section comprising a tube which is adapted to 25 be affixed to the end of a flue and which end section is formed with a reduced end portion which is inserted through the opening in the flue sheet and is formed of a diameter less than that of the opening to provide a 30 space for the accommodation of a gasket; the invention particularly residing in providing a shoulder at the base of the reduced end portion of the flue section consisting of an annular flange projecting in the direction 35 of the reduced end portion, which flange seats in the recess in the flue sheet and encircles and surrounds the inner end portion of the gasket.

The invention is illustrated by way of 40 example in the accompanying drawings, in which:

Fig. 1 is a view in side elevation of the flue end section, partly in vertical section;

Fig. 2 is an end view of same;

Fig. 3 is a view in side elevation of the gasket, partly in vertical section;

Fig. 4 is an end view of same;

Fig. 5 is a detail in section on perspective illustrating the manner of forming the opening in the flue sheet;

Fig. 6 is a view in longitudinal section illustrating the manner of assembling the parts.

More specifically, 7 indicates the tubular

flue end section, 8 denotes the flue on which 55 the end section is fixed, and 9 designates the flue sheet having an opening 10 to receive the outer end portion of the flue end section; 11 indicating the rear or water side face of the flue sheet, and 12 designating the front 60 or fire box side of the flue sheet.

In carrying out my invention, an annular recess 13 is formed along the margin or rim of the opening 10 on the inner face 11 of the flue sheet, which recess constitutes a counterbore and affords a countersunk shoulder 14 in the wall of the opening 10 spaced from the rear surface of the flue sheet. The flue end section is formed with an intermediate body portion 15 of an external diameter substantially corresponding to that of the flue 8 and is provided with a reduced rear end portion 16 adapted to extend into the flue 8 and having an external diameter substantially corresponding to the internal diameter 75 of the flue 8; the flue 8 being shrunk onto the reduced end portion 16 of the flue end section and being affixed thereto by a weld joint 17, as is well known in the art.

The essence of the present invention resides in forming the outer end portion of the flue end section with a reduced end portion 18 of an external diameter less than the diameter of the opening 10 in the flue sheet through which the end portion 18 is designed to extend in spaced relation to the walls of the opening 10. A shoulder 19 is formed at the base of the reduced portion 18 on which is formed an annular end flange 20 which is adapted to seat in the recess 14 80 in the flue sheet with the outer end face of the flange 20 abutting against the bottom wall or shoulder of the recess and with the peripheral face of the flange 20 snugly fitting the side wall of the recess 14. The inner face of the flange 20 being spaced from the outer periphery of the reduced extension 85 18 provides an annular channel 21, the bottom wall of which is adapted to span the gap formed between the walls of the extension 18 and of the opening 10. An annular gasket 22 formed of relatively soft metal such as 90 copper, is positioned to encircle the reduced extension 18 with its inner end seated in the channel 21 and encircled by the flange 20, which gasket is designed to fill the space 95 between the walls of the extension 18 and the opening 10, as particularly shown in Fig. 6,

with the outer end of the gasket extending substantially flush with the outer face 12 of the flue sheet. The outer end portion of the reduced extension 18 is beaded over the outer face 12 of the flue sheet, as indicated in dotted lines in Fig. 6; the bead completely covering the outer end portion of the gasket 22.

It will be observed that by this construction the gasket 22 will be completely housed within the space encircled by the wall of the opening 10 so as not to be exposed either to the water side or fire box side of the flue sheet.

I claim:—

15 A flue connection comprising a flue sheet having a flue opening formed therethrough, a recess formed in the water-side face of the sheet and an abrupt shoulder between the opening and recess; the faces of said opening and recess being at right angles to the faces of the flue sheet and the face of said

shoulder being parallel with the faces of the flue sheet, a flue having an end flange and shoulder for conformity with the recited recess and shoulder of the flue sheet and a channel formed in the flue-end inside of said end flange, a flue extension having its outer face spaced from the face of the flue opening and parallel therewith for a length corresponding with the thickness of the flue sheet, the remaining length of the outer face of said extension being longitudinally inclined and a gasket having a portion sectionally shaped to fit said channel and its remaining portion normally axially tapered, whereby upon a beading and expanding of the longitudinally tapered portion of the flue, said gasket will be completely housed and extend to both sides of the shoulders of said recess and flue end. 35

OTTO F. FUETTERER.
